UNITED STATES PATENT OFFICE.

WILSON E. SYMONS, OF CHICAGO, ILLINOIS.

RAILWAY BUMPING-POST.

No. 846,260.

Specification of Letters Patent.

Patented March 5, 1907.

Application filed October 31, 1906. Serial No. 341,464.

To all whom it may concern:

Be it known that I, WILSON E. SYMONS, a citizen of the United States, residing at Chicago, in the county of Cook and State of Illinois, have invented a new and useful Railway Bumping-Post, of which the following is a specification.

This invention relates more particularly to that class of bumping-posts disclosed in and 10 covered broadly by a prior patent granted to me in November 14, 1905, and numbered 804,685, though there are features in the present invention unquestionably applicable to other types of posts.

15 One of the principal objects is to provide a structure having parts that can be more readily and conveniently cast, said parts when assembled preferably having a slight relative play or movement and yet constituting a thoroughly effective apparatus for 20 the purposes specified.

25 A further and important object is to provide a structure which is mounted on the rails of the track and is so braced that the rails and connections will not be closed or pulled toward each other when the posts receive a heavy blow or shock.

Still another object is to provide securing 30 means for the post that can be readily applied to rails of different sizes and is so associated with the other parts that while the same are effectively connected thereto they may be readily detached if it is found convenient or necessary to do so.

35 The preferred form of construction is illustrated in the accompanying drawings, wherein—

Figure 1 is a top plan view of a section of a railroad-track, showing the improved post in 40 place. Fig. 2 is a front elevation of said post with the bracket-mountings in section. Fig. 3 is a side elevation of the structure. Fig. 4 is a longitudinal sectional view therethrough. Fig. 5 is a cross-sectional view on the line 5 5 45 of Fig. 4. Fig. 6 is a detail sectional view on the line 6 6 of Fig. 4. Fig. 7 is a side elevation of one of the bracket-mountings with the pivotal connection of the associated arm illustrated in section.

50 Similar reference-numerals designate corresponding parts in all the figures of the drawings.

The present structure is applicable to a railway-track at substantially any point and 55 is secured directly to the wheel-rails of the track. For this purpose bracket-mountings

8 are employed, having portions 9 that are arranged to fit against the webs of the rails, said portions being provided with vertical slots 10 to receive the fastening-bolts 11 60 passed therethrough and through the rails. These brackets, furthermore, are preferably provided with spaced hooks 12, arranged to engage beneath the base-flanges of the rails, as shown. By having the slots 10 the brackets 65 can be secured to rails of different weights or sizes, as shown in Fig. 5. In case of application to lighter rails, as indicated in dotted lines, shims 13 are introduced between the base-flanges and the brackets. These 70 brackets are provided with upstanding hooks 14, forming journal-sockets 15, which are provided with contracted mouths 16 opening through the tops of said bracket.

A carrier member is employed comprising 75 upwardly-convergent side arms 17, carrying at their upper ends a stem 18 and having the space between their lower ends bridged by a strut 19. A brace 20 connects an intermediate portion of the strut and the convergent 80 ends of the arms. The carrier member is preferably cast in a single piece, and its lower wider end is provided with outstanding pintles 21, that are rotatable in the sockets 15 of the bracket. It will be observed by reference 85 to Fig. 7 that these pintles are cam-shaped, so that their width in one direction is less than their width in another. The major axes of the pintles are disposed longitudinally of the side arms, and consequently when 90 said side arms are at a rear inclination, as shown in Fig. 7, the pintles will be interlocked in the sockets and cannot be removed therefrom. Nevertheless if the carrier member is swung to a forwardly-inclined position the 95 minor axes or narrower portions of said pintles will be aligned with the contracted mouths 16 of the sockets, and consequently said pintles can be readily passed therethrough, so that the carrier member may be detached 100 from the said brackets.

Associated with the carrier member is a car-engaging member 22, comprising a curved head having a socket 23 between its ends, which socket receives the stem 18 of the carrier member. A shoulder 24 is formed upon the rear side of the car-engaging member 22, just above the socket, and ears 25 are located on opposite sides of said socket and shoulder 24. The rear or upper end of the stem 18 of 105 the carrier member is also provided with a shoulder 26, which shoulder is located be-

tween the ears 25 and in spaced and opposing relation to the shoulder 24. A key 27, passing through the ears 25, passes between the shoulders 24 and 26 and is suitably retained 5 in position by pins 28 or other devices. In actual practice the various parts preferably do not fit snugly in order to allow slight play between them, as this is believed to be advantageous in the operation of the post.

- 10 The upper end of the car-engaging member or head 22 has a dovetail socket 29 formed in its front face to receive a suitable buffer 30, preferably of wood, which buffer is at a sufficient height to engage the car-body. 15 The opposite or lower end of the car-engaging member or head 22 is provided with a series of sockets 31, and a base 32 is located beneath the same and has similar sockets 33 in its upper side. Springs 34 are located in said 20 sockets, and thus serve to yieldingly support the car-engaging member or head. The base 32 is suitably secured to beams 34^a, arranged longitudinally between the rails and bolted to the ties 35 of the track. The base 25 32 is furthermore preferably provided with upstanding guide elements 36, located on opposite sides of the car-engaging member or head and provided with longitudinally-disposed guideways 37. The lower end of the 30 head has outstanding lugs 38, that slidably engage in these guideways, their upward movement being limited by transverse stop bolts or pins 39, carried by the upper ends of the guide elements and extending across the 35 upper ends of the guideways 37, as shown. So far as the yielding mounting of the head or car-engaging member is concerned it is substantially the same as that disclosed in the prior patent, of which mention has already 40 been made.

It will be noted that this structure can be applied to a track at substantially any point desired, and, as already shown, the brackets are attachable to all grades of rails. The 45 parts can be readily cast and easily assembled, being held together by a very substantial connection which admits of some little flexibility or play. The particular construction of the carrier member or frame is important, for by providing the cross strut or brace there is no danger of the side arms, and consequently the rails, being drawn toward each other when the post receives a heavy blow or shock. In this structure, furthermore, the 50 parts can be easily disassociated, if it is desired to remove the post, for it will be evident that the head can be readily detached from the carrier member and that the carrier member may be removed from the brackets by 55 merely swinging the same to a forward position, so that the pintles may be passed through the throats 16 of the sockets 15.

From the foregoing it is thought that the construction, operation, and many advantages of the herein-described invention will be

apparent to those skilled in the art without further description, and it will be understood that various changes in the size, shape, proportion, and minor details of construction may be resorted to without departing from the spirit or sacrificing any of the advantages of the invention.

Having thus fully described my invention, what I claim as new, and desire to secure by Letters Patent, is—

1. In a structure of the character set forth, the combination with a swinging carrier member, of means for securing the same to a railway-track, a car-engaging member, means detachably connecting the members, 80 and a yielding support for the car-engaging member.

2. In a structure of the character set forth, the combination with a swinging carrier member, of means for securing the same 85 to a railway-track, a car-engaging member, means detachably and loosely connecting the members to permit a slight relative play between them, and a yielding support for the car-engaging member.

3. In a structure of the character set forth, the combination with a swinging carrier member, of means for securing the same to a railway-track, a car-engaging member, one of said members having a socket, the 95 other having a portion that engages in the socket, and means for maintaining said portion in the socket.

4. In a structure of the character set forth, the combination with a car-engaging 100 member having a socket, of a swinging carrier member having one end engaged in the socket, and means for pivotally mounting the other end of the carrier member.

5. In a structure of the character set 105 forth, the combination with a car-engaging member having a socket, of a carrier member having a stem loosely engaged and secured in the socket to permit a slight relative play between said members.

6. In a structure of the character set forth, the combination with a car-engaging member, of a carrier member, one of said members having a socket, the other having a portion located in the socket, and a key engaging the members for preventing their disassociation.

7. In a structure of the character set forth, the combination with a car-engaging member, of a carrier member, one of said members having a socket and a shoulder adjacent to the socket, the other having a portion located in the socket and a shoulder spaced from and opposed to the first-mentioned shoulder, and a key located between the shoulders for preventing the disassociation of the members.

8. In a structure of the character set forth, the combination with a car-engaging member, of a carrier member, one of said

members having a socket and ears on opposite sides of the socket, the other member having a stem located in the socket, and a key arranged in the ears and engaging the member having the stem, said key preventing the disassociation of the members.

9. In a structure of the character set forth, the combination with a yieldingly-supported car-engaging member having a socket, a shoulder disposed adjacent to the socket and ears located on opposite sides of the socket, of a pivotally-mounted carrier member having a stem that passes through the socket and having a shoulder on its rear end disposed in spaced relation to the shoulder of the car-engaging member and between the ears, and a key passing through the ears and between the shoulders.

10. In a structure of the character set forth, the combination with a car-engaging member, comprising a head having a socket between its ends, one end of the head constituting a car-engaging bumper, of a yielding support engaging the other end of the head, and a pivotally-mounted carrier having a stem extending into the socket and secured to the head.

11. In a structure of the character set forth, the combination with a tapered carrier having a stem at its smaller end, of a car-engaging member having a socket that receives the stem, and means for pivotally mounting the wider end of the carrier.

12. In a structure of the character set forth, the combination with a carrier comprising convergently-disposed side arms and a strut connecting their spaced ends, of a car-engaging member carried by the narrow end of the carrier member, and means for pivotally mounting the wider end thereof.

13. In a structure of the character set forth, the combination with a carrier comprising convergently-disposed side arms, a strut connecting their spaced ends and an intermediate member connecting the strut and the convergent ends of the side arms, of a car-engaging member carried by the narrower end of the carrier member, and means for pivotally mounting the wider ends of the carrier member.

14. In a structure of the character set forth, the combination with a carrier member comprising convergently-disposed side arms having a stem at their convergent ends, a strut connecting the spaced end of the side arms and a brace connecting an intermediate portion of the strut and the convergent ends of the side arms, of a car-engaging member having a socket that receives the stem of the carrier member, a yielding support for the car-engaging member, and means for pivotally securing the wider end of the carrier member to the rails of a track.

15. In a structure of the character set forth, the combination with a bracket-mount-

ing, of a car-engaging member, and a carrier member for the car-engaging member and having a pivotal connection with the bracket-mounting, said carrier member being interlocked against detachment from the bracket-mounting when in one position, and being detachable therefrom when located in another position.

16. In a structure of the character set forth, the combination with a bracket member, of a carrier member, one of said members having a socket provided with a contracted mouth, the other member having a pintle that engages in the socket and is interlocked therewith when in one position but can be passed through the mouth when in another position, and a car-engaging member carried by the carrier member.

17. In a structure of the character set forth, the combination with a bracket member, of a carrier member, one of said members having a socket provided with a contracted mouth, the other member being provided with a pintle having a width in one direction that is greater than the mouth and substantially equal to the diameter of the socket and having a less width in another direction that permits its passage through the mouth, and a car-engaging member mounted on the carrier member.

18. In a structure of the character set forth, the combination with spaced bracket members having sockets provided with contracted mouths, of means for securing the same to a railway-track, a carrier member having pintles that are cam-shaped in cross-section so that they will pass through the contracted mouths of the bracket member when the carrier member is in one position, and will fit snugly in the socket when in different position, a car-engaging member carried by the carrier member, and means for yieldingly supporting the car-engaging member.

19. In a structure of the character set forth, the combination with brackets arranged to fit against rails of different sizes and having a plurality of upright slots to receive holding-bolts, said brackets having sockets, of a carrier member having pintles that engage in the sockets, and a car-engaging member carried by the carrier member.

20. In a structure of the character set forth, the combination with brackets having sockets of means for securing the brackets to a railway-track, a tapering carrier member having pintles engaged in the sockets and having a stem at its contracted end, a car-engaging member comprising a head having a socket that receives the stem, a key for securing the stem in the socket, and yielding means for supporting the head.

21. In a structure of the character set forth, the combination with a swinging carrier member, of means for mounting the same

on a railway-track, a car-engaging member, means detachably connecting the members, and yielding means for resisting the movement of the car-engaging member when struck by a car.

22. In a structure of the character set forth, the combination with a swinging carrier member, of means for mounting the same on a railway-track, a car-engaging member, means detachably and loosely connecting the members to permit a slight relative play be-

tween them, and means for yieldingly resisting the movement of the car-engaging member when struck by a car.

In testimony that I claim the foregoing as my own I have hereto affixed my signature in the presence of two witnesses.

WILSON E. SYMONS.
